(No Model.)

D. C. KLINE.

TUBULAR LANTERN.

No. 365,605.

Patented June 28, 1887.

UNITED STATES PATENT OFFICE.

DAVID C. KLINE, OF ROCHESTER, NEW YORK.

TUBULAR LANTERN.

SPECIFICATION forming part of Letters Patent No. 365,605, dated June 28, 1887.

Application filed July 7, 1886. Serial No. 207,303. (No model.)

To all whom it may concern:

Be it known that I, DAVID C. KLINE, of the city of Rochester, in the county of Monroe and State of New York, have invented new and useful Improvements in Tubular Lanterns, of which the following is a specification.

This invention relates to an improvement in a tubular lantern, in which the side tubes are divided near the base of the lantern, and the globe-support is attached to the upper portions of the side tubes, so that by lifting the upper portions of the side tubes from the base the globe is raised from the burner, thereby giving access to the wick for trimming, lighting, extinguishing, &c.

The object of my invention is to improve the devices whereby the parts of the lantern are connected and the globe is held in place.

My invention consists, to that end, of the improvements, which will be hereinafter fully set forth, and pointed out in the claims.

In the accompanying drawings, Figure 1 is a side elevation of the lantern provided with my improvements. Fig. 2 is a similar view showing the globe raised. Fig. 3 is a horizontal section in line *x x*, Fig. 1. Fig. 4 is a vertical section in line *y y*, Fig. 1, on an enlarged scale. Fig. 5 is a side elevation of the lower part of the lantern at right angles to Fig. 1. Fig. 6 is a perspective view of one of the spring-guides. Fig. 7 is a vertical section in line *z z*, Fig. 1.

Like letters of reference refer to like parts in the several figures.

A represents the base of the lantern, containing the oil-pot A', the air-chamber B resting on the same, and the burner C.

b b represent the short horizontal portions of the air-supply tubes, which are secured to the sides of the air-chamber, and which have their outer and upper portions cut away to form outwardly-projecting semicircular bottom portions, *b*, which are open at the top.

D represent the side tubes connected at their upper ends to a vertical tube, *d*, which is provided at its lower end with a bell or funnel, *d'*, in the usual manner.

E E represent the horizontal lower portions of the side tubes, which open inwardly or toward the air-chamber and rest in the semicircular portions *b'* of the base when the globe is

lowered. The joint between the horizontal tubes E and *b* is covered by curved shields E', which are secured to the upper sides of the tubes E and protect the joint against rain, 55 dust, &c.

F F' represent bent bridge-pieces secured with their ends to the horizontal tube portions E, and connecting the same on opposite sides of the burner-cone, as clearly represented in Fig. 3.

G represents the globe-supporting plate, which is hinged to the bridge-piece F at *g*, so that it can be tilted or inclined when inserting or removing the globe. The raised portion *f* of the bridge-piece F' serves as a support for the plate G when the latter is in a horizontal position, as represented in Fig. 5. The bridge-pieces F F' hold the burner securely in its seat and prevent it from dropping 70 out when the globe is broken, thus preventing accidents from this cause.

H represents the globe, and *h* the annular spring-catch secured to the under side of the bell *d'*, and holding the upper end of the globe 75 in the usual manner.

I represents spring-guides secured to the base of the lantern and embracing the lower portions of the side tubes, so as to guide the same in their movements toward and from the 80 base. Each guide I is bent of a single piece of wire, which is secured with its lower ends to the base of the lantern. Each guide I is composed of upright arms *i*, arranged on the front and rear sides of the same side tube, a 85 horizontal bow, *i'*, extending outwardly from the upper ends of the arms *i* and bearing against the outer side of the side tube, and coils *i''*, connecting the lower ends of the arms *i* with the ends *i''*, which are secured to the 90 base of the lantern. The coils *i''* hold the bows *i'* against the slightly-inclined side tubes as the same are raised or lowered.

J represents a wire bail secured with its lower looped ends, *j*, to the upper ends of the 95 guides I, and resting with its upper portion on the top of the central tube, *d*, when the globe is lowered, as represented in Fig. 1. The side portions, *j'*, of the bail pass through guide-loops K, secured to the inner sides of the tubes 100 D. The upper portion of the bail J is locked on the tube *d* by a projection, *l*, formed on the

top of said tube. The coils i^2 of the guide I permit the bail J to yield and pass over the projection l and draw the bail tightly against the tube d after it has passed over the projection, thereby securely holding the upper and lower portions of the lantern together. In this respect the guides I operate as springs for the bail J. Upon disengaging the bail J from the tube d the upper portion of the lantern 10 can be raised from the base, as represented in Fig. 2, thereby exposing the burner-cone and affording access to the wick for trimming, lighting, and extinguishing, and permitting the removal of the burner from the oil-pot. 15 The upper portion of the bail J is provided with a thumb-piece, m, for convenience in handling it.

I claim as my invention—

1. The combination, with the base of the lantern, provided with tubes b, of the vertically-movable side tubes, a globe-support secured to the side tubes, and the spring-guides I, secured to the base and provided with bows i' , which embrace the side tubes, substantially as set forth.

2. The combination, with the base of the lantern, provided with tubes b, and the vertically-movable side tubes provided with a globe-support, of the wire guides I, secured to the base, and each composed of upright side arms, i, bows i' , and coils i^2 , substantially as set forth.

3. The combination, with the base of the lantern, provided with tubes b, and the vertically-movable side tubes provided with a globe-support, of spring-guides I, secured to

the base and embracing the side tubes, and a fastening-bail, J, secured to said guides and engaging with the upper portions of the tubes, thereby securing both parts of the lantern together, substantially as set forth.

4. The combination, with the base of the lantern, provided with tubes b, and the vertically-movable side tubes provided with a globe-support, of a projection, l, secured to the upper portion of the side tubes, guides I, secured to the base, and a fastening-bail, J, adapted to engage behind the projection l, substantially as set forth.

5. The combination, with the base A, provided with a burner, C, of the vertically-movable side tubes, D, a bridge-piece, F, connecting the side tubes on one side of the burner, and provided with a hinged plate, G, and a bridge-piece, F', connecting the side tubes on the other side of the burner and forming a support for the plate G, substantially as set forth.

6. The combination, with the base A, provided with an air-chamber, B, and horizontal tubes b, having semicircular bottom extensions, b', of the vertically-movable side tubes, D, having horizontal lower portions, E, adapted to rest in the extensions b', and provided with protecting-shields E', substantially as set forth.

Witness my hand this 2d day of July, 1886.

DAVID C. KLINE.
